UNITED STATES PATENT OFFICE.

WILLIAM SPENCER, OF BROOKLYN, ASSIGNOR TO WILLIAM W. FARMER, OF NEW YORK, N. Y.

DESIGN FOR A PRINTER'S BORDER.

SPECIFICATION forming part of Design No. 22,807, dated September 26, 1893.

Application filed September 4, 1893. Serial No. 484,788. Term of patent 3½ years.

To all whom it may concern:

Be it known that I, WILLIAM SPENCER, a subject of the Queen of Great Britain, (having resided one year last past in the United States, and declared my intention of becoming a citizen thereof,) residing at Brooklyn, in the county of Kings, State of New York, have invented and produced a new and original Design for Printers' Borders or Rules, of which the following is a specification, reference being had to the accompanying drawings, forming part thereof.

The leading feature of my design for a printer's border or rule is a figure of the form of a frustum of a triangle, having a concave side.

Figure 1 represents a face view of a printer's border, embodying my design. Fig. 2 represents a side elevation thereof.

In the drawings: A designates figures of the form of frustums of triangles having concavities B on the sides thereof. The figures A are separated by triangular spaces C.

What I claim is—

The design for a printer's border, as shown and described.

WILLIAM SPENCER.
